US00D939017S

(12) **United States Design Patent** (10) **Patent No.:** **US D939,017 S**
Liang (45) **Date of Patent:** **** Dec. 21, 2021**

(54) **VR ADJUSTABLE HEAD STRAP**

(71) Applicant: **Jundi Liang**, Guangdong (CN)

CN 303969950 * 2/2016
CN 304249974 * 8/2017

(72) Inventor: **Jundi Liang**, Guangdong (CN)

(Continued)

(73) Assignee: **Shenzhen Masitiya Network Technology Co., Ltd.**, Guangdong (CN)

(**) Term: **15 Years**

(21) Appl. No.: **29/763,964**

(22) Filed: **Dec. 28, 2020**

(51) LOC (13) Cl. **16-06**

(52) U.S. Cl.

USPC **D16/339**

Primary Examiner — Sanjeev Paul

(57) **CLAIM**

The ornamental design for a VR adjustable head strap, as shown and described.

DESCRIPTION

FIG. 1 is a perspective view of a VR adjustable head strap showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is an enlarged view of the VR adjustable head strap shown in FIG. 2

FIG. 9 is another enlarged view of the VR adjustable head strap shown in FIG. 4

FIG. 10 is another enlarged view of the VR adjustable head strap shown in FIG. 1; and

FIG. 11 is another enlarged view of the VR adjustable head strap shown in FIG. 6; and,

FIG. 12 is a perspective view showing the separated state of VR adjustable head strap.

1 Claim, 12 Drawing Sheets
